(57) **CLAIM**

The ornamental design for an infusing container, as shown and described.

DESCRIPTION

FIG. 1 is a front perspective view of a first embodiment of an infusing container showing our new design;

FIG. 2 is a front view thereof;

FIG. 3 is a rear view thereof;

FIG. 4 is a right side view thereof;

FIG. 5 is a left side view thereof, showing cross-sectional plane 8-8;

FIG. 6 is a top plan view thereof;

FIG. 7 is a bottom plan view thereof;

FIG. 8 is a cross section view showing the section taken along the line 8-8 of FIG. 5;

FIG. 9 is a top plan view thereof with the top cap removed for ease of illustration;

FIG. 10 is a top perspective view thereof;

FIG. 11 is a front perspective view of a second embodiment of an infusing container showing our new design;

FIG. 12 is a front view thereof;

FIG. 13 is a rear view thereof;

FIG. 14 is a right side view thereof;

FIG. 15 is a left side view thereof, showing cross-sectional plane 18-18;

FIG. 16 is a top plan view thereof;

FIG. 17 is a bottom plan view thereof;

FIG. 18 is a cross section view showing a section taken along line 18-18 of FIG. 15;

FIG. 19 is a top perspective view thereof with the top cap removed for ease of illustration; and,

FIG. 20 is a top plan view thereof.

The broken lines in the drawing depict portions of the infusing container that form no part of the claimed design.
